UNITED STATES PATENT OFFICE.

EDWARD D. SOUTHWICK, OF GRANITE CITY, ILLINOIS.

GUTTER-HANGER.

No. 918,786.

Specification of Letters Patent. Patented April 20, 1909.

Application filed October 1, 1908. Serial No. 445,700.

To all whom it may concern:

Be it known that I, EDWARD D. SOUTHWICK, a citizen of the United States, residing at Granite City, in the county of Madison 5 and State of Illinois, have invented a new and useful Gutter-Hanger, of which the following is a specification.

This invention relates to that class of gutter or eaves-trough supports in which there 10 is employed a hanger having a stay combined with it and adapted to be secured within the trough to prevent the latter from yielding to inward or outward pressure.

In devices of this character, as heretofore 15 constructed, the stay is rigid relatively to the hanger, so that no adjustment of the parts can be effected to cause the hanger to occupy a position parallel with the adjacent wall of a building in connection with which the 20 trough is used.

It is the object of the present invention so to assemble the stay and the hanger that the latter may readily be adjusted longitudinally of the former, thus to cause the shank of the 25 hanger to occupy a plane parallel with the adjacent wall of the building, and also to control the length of the projecting ends of the hanger that pass through the gutter and are bent or otherwise secured around the edges 30 thereof.

With the above and other objects in view, as will appear as the nature of the invention is better understood, the same consists in the novel construction and combination of parts 35 of an eaves-trough hanger or support, as will be hereinafter fully described and claimed.

In the accompanying drawing, forming a part of this specification, and in which like characters of reference indicate corresponding 40 parts:—Figure 1 is a view in perspective displaying a trough supported from the roof of a building with the hanger of the present invention. Fig. 2 is a perspective detail view of the hanger shown in Fig. 1, a portion 45 being in section. Fig. 3 is a perspective detail view of a slightly modified form of the support.

Referring to the drawings, R designates a portion of the roof of a building, W one of the 50 walls of a building, and T a portion of an eaves-trough or gutter, and as these parts may be of the usual, or any preferred construction, further description thereof is deemed unnecessary.

55 The gist of the present invention resides in the novel form of support that is adapted

also to brace the trough or gutter against any tendency to yield inwardly or outwardly from any cause. The form of the support shown in Figs. 1 and 2 comprises a hanger 1 and a stay 2. As shown, the hanger is constructed from a length of wire that is bent upon itself and then twisted to form a shank 3, the ends of the shank being extended at right angles thereto to provide two alined 60 arms 4. These arms are housed for the greater portion of their length by the stay 2, which is constructed from a strip of sheet metal, such as tin or the like, and is folded upon itself in such manner as to provide two 65 seats 5 in which the arms are slidably mounted. The intermediate portion of the stay is cut away to provide a longitudinal slot 6, in which the lower portion of the shank is adapted to work, and each of the arms adjacent to the shank is provided with an offset 7, the two bumps operating positively to prevent the stay from having any 70 rocking movement relatively to the arms, while not in the least interfering with its 75 free sliding movement thereon.

In assembling the support with a gutter, the latter is provided with two alined orifices to receive the free terminals of the arms 4 and after the shank has been secured to the 80 roof, as by means of a nail 8 and a staple 9, the free ends of the arms are passed through the orifices in the trough and after the latter has been adjusted properly with relation to the edge of the roof, this being accomplished 85 by moving the trough to or from the wall, in which case the shank will work in slot 6, and the ends of the arms are bent around the bead of the trough and at its rear edge.

As shown at 10, and 11, this manner of 90 securing the support to the trough obviates the necessity of the employment of solder, but if preferred this may be used if of advantage. By reason of the two offsets 7, which will be of such size as to hold the 100 arms in operative contact with the inner walls of the seats 5, the shank will be held against any rocking movement relatively to the stay, and this is a feature of importance inasmuch as it will brace the trough or gutter 105 against any tendency to end-wise movement, as from wind pressure.

In the form of the invention shown in Fig. 3, the stay 12 is formed of a strip of metal which is bent upon itself to provide two 110 seats 13, in which arms 14 of the shank 15 are housed for a portion of their length. The

intermediate part of the stay is provided with an upstanding fin or guide 16 which is designed to work between the two arms 14 at their point of juncture with the shank, 5 and thereby hold the stay from any rocking movement relatively to the shank.

In the embodiment of the invention shown in Fig. 2 the longitudinal movement of the shank relatively to the stay is limited 10 by the contact between the shank and the opposed walls 5, the latter being also true in the embodiment of the invention shown in Fig. 3, wherein the bend of the arms at their point of juncture with the shank contact with the opposed walls of the seats 13. 15

The improvements herein defined are simple in character, but will be found thoroughly efficient for purposes designed and may readily and cheaply be manufactured 20 without the employment of special machinery for the purpose.

I claim:—

1. A gutter support embodying a hanger

provided with lateral arms, a stay slidably mounted on the arms, said hanger serving to 25 limit the sliding movement of the arms relatively to the stay.

2. A gutter support embodying a hanger provided with lateral arms, a stay slidably mounted on the arms, and means for holding 30 the arms from rocking movement relatively to the stay.

3. A gutter support embodying a hanger provided with lateral arms, a stay slidably mounted on the arms, means for holding the 35 arms from rocking movement relatively to the stay, said hanger serving to limit the sliding movement of the arms with relation to the stay.

In testimony that I claim the foregoing as 40 my own, I have hereto affixed my signature in the presence of two witnesses.

EDW. D. SOUTHWICK.
